J. D. PEDERSEN.

FIREARM.

APPLICATION FILED DEC. 17, 1919.

1,391,496.

Patented Sept. 20, 1921.

Inventor:

John D. Pedersen,
By his Atty, *Richards*.

UNITED STATES PATENT OFFICE.

JOHN D. PEDERSEN, OF JACKSON, WYOMING.

FIREARM.

1,391,496.

Specification of Letters Patent. Patented Sept. 20, 1921.

Original application filed July 30, 1915, Serial No. 42,774. Renewed July 17, 1919, Serial No. 311,689.
Divided and this application filed December 17, 1919. Serial No. 345,550.

To all whom it may concern:

Be it known that I, JOHN D. PEDERSEN, a citizen of the United States, residing in Jackson, in the county of Lincoln and State 5 of Wyoming, have invented certain new and useful Improvements in Firearms, of which the following is a specification.

This application, as regards some of the principal features set forth, relates to a 10 modification of the breechblock mechanism which is described and set forth in my Patent No. 1,348,733, dated August 3, 1920, and granted on my copending application (renewal) Serial No. 311,689, filed July 17th, 15 1919, and which modification is referred to in my said patent but is not specifically claimed therein, and to which patent reference may be had.

One class of firearms to which my present 20 improvements are applicable includes auto-loading pistols.

An improved auto-loading pistol of this kind is described in my said patent. Therefore, for convenience of illustration, I have 25 herein illustrated my present improvements as arranged and applied to the particular kind of auto-loading pistol which is shown in the drawings of said application, to which reference may be had.

One object of the present improvements 30 is to furnish for use in firearms and especially for use in auto-loading pistols, an improved slide-and-block mechanism in which the breechblock is movable with the slide, 35 and is movable rearwardly prior to rearward movement of the slide and being in engagement therewith transmits rearward movement to the slide, and after such transmission the breechblock is retarded in its 40 rearward movement, and retarded relatively to the slide while the slide is moved rearwardly, and during the cartridge shell ejecting period, and locked to the slide for concurrent rearward movement of the slide and 45 breechblock; this being accomplished by engagement of the breechblock with the frame of the pistol, and by means for connecting the breechblock to the slide coacting with the breechblock and slide.

Other objects and advantages are indicated or pointed out in the course of the following description.

An embodiment of the invention is illus-

trated in the accompanying drawings in which:

Figure 1, is a side view, partly broken away to show the details of a pistol provided with my slide-and-breechblock mechanism, the slide and breechblock being in forward or normal position, and the firing member 60 or hammer being in firing position.

Fig. 2, is a detail sectional view, on an enlarged scale, on the line 2-2 of Fig. 1, looking in the direction of the arrow.

Fig. 3, is a fragmentary detail sectional 65 view, on a larger scale than Fig. 1, of a pistol provided with my slide-and-breechblock mechanism, showing the breechblock in course of rearward movement into engagement with the abutment face of the 70 frame for retarding the breechblock after transmission of rearward movement from the breechblock to the slide, but prior to retardation of the breechblock relative to the 75 slide while the slide is moved rearwardly.

Fig. 4, is a fragmentary detail sectional 80 view, on the same scale as Fig. 3, of a pistol provided with my slide-and-breechblock mechanism, showing the breechblock moved rearwardly during movement of the firing member or hammer to fired position, the breechblock not yet being free from engagement 85 with the abutment face of the frame for retarding the breechblock in its rearward movement.

Fig. 5, is a fragmentary detail sectional 90 view of a pistol provided with my slide-and-breechblock mechanism, showing the breechblock free from engagement with the abutment face of the frame for retarding rearward movement of the breechblock, and subsequent to retardation of the breechblock relative to the slide, the breechblock and slide being locked together and moved concurrently rearward, and the firing member 95 or hammer being moved to firing position by rearward movement of the slide.

Fig. 6, is a detail plan view of the breechblock.

Fig. 7, is a detail view of the rear end of 100 the breechblock.

Similar reference characters or numerals refer to similar parts throughout the several views.

The frame or receiver B of the pistol is 105 provided with an abutment face 2'.

The slide C is movable rearwardly and forwardly on the frame or receiver B, and is provided with an inclined upper face 33^a, a blocking-face 3^b, an inclined lower face 5 33^c, a vertical or stop-face 3^r, and a guide-face 10.

The breechblock E is of the form shown in the drawings, and is received in and is movable with the slide C, and comprises the 10 firing-pin P. The breechblock E is provided near its rear end with an inclined lower-face or abutment-face 5^d, which is engageable with the abutment face 2^r of the frame or receiver B, and is provided with an inclined 15 front face 5^e which is engageable with the inclined lower face 33^r of the slide, and is provided with an upper face 5^a which is engageable with the blocking face 3^b of the slide. A rear or end face 5^f is provided on 20 the breechblock E which is engageable with the vertical or stop-face 3^r of the slide. The intersection of the faces 5^a and 5^f of the breechblock E forms a junction point or engaging end 11, which engages the guide-face 25 10 of the slide C, which junction point or engaging end 11 is somewhat rounded the better to engage the guide-face 10. The faces 33^r, 33^a and 3^b of the slide C afford a recess or space for the reception therein of 30 the breechblock E, when the breechblock is in raised or lifted position for concurrent movement with the slide C, the faces 3^b and 33^a providing respectively an engaging surface for the face 5^d of the breechblock to 35 limit upward movement of the breechblock, and clearance space for the breechblock.

The slide C is provided with a roller 3^c which is engageable with the front face of the firing member or hammer H, when the 40 slide is moved rearwardly and the firing member or hammer is in fired position, which roller 3^c rides over the firing member or hammer and moves it to firing position, but instead of a roller a contacting or rear face 45 of the slide may be arranged for this purpose. The firing member or hammer H when in fired position is engageable with the firing pin P.

Links L^e are pivotally attached at their 50 upper ends to the slide C and at their lower ends to the breechblock E, a link to each side of the slide and to each side of the breech-block.

The links L^e are preferably attached to 55 the slide C by a bolt C^s, and are attached to the breechblock by pins C^t, but any form of attachment may be used which will provide pivotal movement of the links at their upper and lower ends. The sides of the slide may 60 be slotted as at 12, to allow pivotal or swinging movement of the links L^e.

In operation: The force of the powder gases is first exerted upon the breechblock E to move it rearwardly.

The face 5^f of the breechblock being in engagement with the face 3^r of the slide rearward movement is thereby transmitted from the breechblock to the slide. As the breech block moves rearwardly the face 5^d of the breechblock engages the face 2^r of the frame and the breechblock is retarded in its rearward movement and the rear end thereof is pulled up or lifted by the links L^e, and the face 5^d of the breechblock rises on the abutment face 2^r of the frame of the pistol. The junction or point 11 of the faces 5^a and 5^f of the breechblock being in engagement with the guide-face 10 of the slide C, there is a retardation of the breechblock relative to the slide C while the slide is moved rearwardly and when the face 5^f of the breechblock clears or is free from engagement with the abutment face 2^r of the frame of the pistol, and the rear end of the breechblock is locked in the recess or space comprised by the faces 33^r, 33^a and 3^b of the slide, and pulled along or drawn concurrently rearwardly with the slide. During the transmission of rearward movement from the breechblock E to the slide C, the links L^e receive the thrust of the breechblock E and act as a thrust member for holding down the breechblock, and after temporary stopping or retardation of the breechblock by the abutment face 2^r of the frame of the pistol, and as the slide moves rearwardly, the links L^e pull upwardly or lift the rear end of the breechblock and act as a tension member.

The guide-face 10 of the slide by engagement with the junction point or engaging end 11 of the faces 5^a and 5^f of the breechblock coacts with the links L^e to guide the breechblock E in its rearward movement relatively to the slide C and into position wherein the breechblock is locked to the slide C and moves concurrently rearwardly therewith. It is obvious that only one link L^e may be used, but the use of two links is preferred.

In my said patent, reference being had thereto, I have described and shown guide-links L^e as a modification for controlling and regulating the movement of the breechblock E, and reservation being made in my said co-pending application for separate application for Letters Patent for said modification, the present application is in accordance with such reservation.

When the slide C has reached its most rearward or retracted position it is moved 120 forwardly by spring means not shown, and the breechblock E still being locked to the slide is carried forwardly with the slide until the rear end of the breechblock drops into the position shown in Figs. 4 and 3, and finally, into the position shown in Fig. 1, said figures being considered relative to forward movement of the breechblock, the

breechblock E and slide C then being respectively in forward or normal position. The firing member or hammer H having been moved to firing position by the before 5 mentioned rearward movement of the slide C, is locked in firing position by a sear member not shown.

Having thus described my invention, I claim:

10 1. In a firearm, in combination, a frame of said firearm, a slide movable rearwardly on said frame, a breechblock movable with the slide and movable rearwardly prior to rearward movement of the slide and engaging 15 the slide for transmitting rearward movement thereto, means coöperative between the breechblock and said frame for retarding rearward movement of the breechblock after transmission of rearward movement 20 to the slide by said engagement therewith, and means for connecting the breechblock and slide and coacting therewith for providing retardation of the breechblock relative to the slide while the slide is moved 25 rearwardly.

2. In a firearm, in combination, a frame of said firearm, a slide movable rearwardly on said frame, a breechblock movable with the slide and movable rearwardly prior to rearward movement of the slide and engaging 30 the slide for transmitting rearward movement thereto, means coöperative between the breechblock and said frame for retarding rearward movement of the breechblock after transmission of rearward movement 35 to the slide by said engagement therewith, and link means coacting with the breechblock and slide for providing retardation of the breechblock relative to the slide 40 while the slide is moved rearwardly.

3. In a firearm, in combination, a frame of said firearm, a slide movable rearwardly on said frame, a breechblock movable with the slide and movable rearwardly prior to rearward movement of said slide and engaging 45 the slide for transmitting rearward movement thereto, means coöperative between the breechblock and said frame for retarding rearward movement of the breechblock after transmission by the breechblock of rearward movement to the slide by said engagement therewith, and means for connecting the breechblock and slide and coacting therewith for providing retardation of the breechblock relative to the slide while the slide is moved rearwardly, and for locking the breechblock to the slide for concurrent rearward movement of the slide and breechblock.

4. In a firearm, in combination, a frame of 50 said firearm, a slide movable rearwardly on said frame, a breechblock movable with the slide and movable rearwardly prior to rearward movement of said slide and engaging the slide for transmitting rearward movement thereto, means coöperative between the breechblock and slide and coacting therewith for providing retardation of the breechblock relative to the slide while the slide is moved rearwardly, and for locking the breechblock to the slide for concurrent rearward movement of the slide and breechblock.

65 5. In a firearm, in combination, a frame of

breechblock and said frame for retarding rearward movement of the breechblock after transmission by the breechblock of rearward movement to the slide by said engagement therewith, and link means coöperating with 70 the breechblock and slide for providing retardation of the breechblock relative to the slide while the slide is moved rearwardly, and for locking the breechblock to the slide for concurrent rearward movement of the 75 slide and breechblock.

5. In a firearm, in combination, a frame of said firearm, a slide movable rearwardly on said frame and provided with a recess in the interior face of the rearward end thereof, a breechblock movable with the slide and movable rearwardly prior to rearward movement of said slide and engaging the slide for transmitting rearward movement thereto, means coöperative between the breechblock and said frame for retarding rearward movement of the breechblock after transmission by the breechblock of rearward movement to the slide by said engagement therewith, and means for connecting the 80 breechblock and slide and coacting therewith for providing retardation of the breechblock relative to the slide while the slide is moved rearwardly, and for locking the breechblock in said recess for concurrent rearward movement of the slide and breechblock.

6. In a firearm, in combination, a frame of said firearm, a slide movable rearwardly on said frame and provided with a recess in the interior face of the rearward end 100 thereof, a breechblock movable with the slide and movable rearwardly prior to rearward movement of said slide and engaging the slide for transmitting rearward movement thereto, means coöperative between the 105 breechblock and said frame for retarding rearward movement of the breechblock after transmission by the breechblock of rearward movement to the slide by said engagement therewith and link means coöperating with 110 the breechblock and slide for providing retardation of the breechblock relative to the slide while the slide is moved rearwardly, and for locking the breechblock in said recess for concurrent rearward movement of 115 the slide and breechblock.

7. In a firearm, in combination, a frame of said firearm, a slide movable rearwardly on said frame, a breech block movable with the slide and movable rearwardly by powder 120 gases prior to rearward movement of said slide and engaging the slide for transmitting rearward movement thereto, means coöperative between the breechblock and said frame for retarding rearward movement of 125 the breechblock after transmission by the breechblock of rearward movement to the slide by said engagement therewith, and means for connecting the breechblock and slide and coacting therewith for providing 130

retardation of the breechblock relative to the slide while the slide is moved rearwardly.

8. In a firearm, in combination, a frame 5 of said firearm, a slide movable rearwardly on said frame, a breechblock movable with the slide and movable rearwardly by powder gases prior to rearward movement of said slide and engaging the slide for transmitting rearward movement thereto, means co-operative between the breechblock and said frame for retarding rearward movement of the breechblock after transmission by the breechblock of rearward movement to the 10 slide by said engagement therewith, means for connecting the breechblock and slide and coacting therewith for providing retardation of the breechblock relative to the slide while the slide is moved rearwardly, and 15 for locking the breechblock to said slide for concurrent rearward movement of the slide and breechblock.

9. In a firearm, in combination, a frame 20 of said firearm, a slide movable rearwardly on said frame, a breechblock movable with the slide and movable rearwardly by powder gases prior to rearward movement of said slide and engaging the slide for transmitting rearward movement thereto and comprising a firing-pin, means co-operative between the breechblock and said frame for retarding rearward movement of the breechblock after transmission of rearward movement to the slide by said engagement therewith, means for connecting the breechblock 25 and slide and coacting therewith for providing retardation of the breechblock relative to the slide while the slide is moved rearwardly, and for locking the breechblock to the slide for concurrent rearward movement of the slide and breechblock, and a firing member movable to firing position by rearward movement of said slide and engageable with said firing-pin.

45 10. In a firearm, in combination, a frame of said firearm, a slide movable rearwardly and forwardly on said frame, a breechblock movable with the slide and movable rearwardly by powder gases prior to rearward movement of said slide and engaging the slide for transmitting rearward movement thereto and comprising a firing-pin, a firing member movable to firing position and to fired position and engageable with said firing-pin, means co-operative between the breechblock and said frame for retarding rearward movement of the breechblock after transmission by the breechblock of rearward movement to the slide by said engagement therewith, and means for connecting the breechblock and slide and coacting therewith for providing retardation of the breechblock relative to the slide while the slide is moved rearwardly, and for locking 60 the breechblock to the slide for concurrent 65

rearward movement of the slide and breechblock, said firing member being movable to firing position by rearward movement of said slide.

11. In a firearm, in combination, a frame 70 of said firearm provided with an abutment face, a slide movable rearwardly on said frame provided with an inclined lower face, and provided with a blocking-face, and provided with a stop-face, a breechblock movable rearwardly by powder gases prior to rearward movement of said slide provided with a lower face engageable with said abutment face of the frame, and provided with a front face engageable with said inclined 75 lower face of the slide, and provided with an upper face engageable with said blocking-face of the slide, and provided with a rear face engageable with said stop-face of the slide, and link means connected to said 80 slide and connected to said breechblock.

12. In a firearm, in combination, a frame 85 of said firearm provided with an abutment face, a slide movable rearwardly on said frame and provided with an inclined lower face, and provided with a blocking-face, and provided with a stop-face, and provided with rear contacting means, a breechblock movable rearwardly by powder gases prior to rearward movement of said slide and comprising a firing-pin, and provided with a lower face engageable with said abutment 90 face of the frame, and provided with a front face engageable with said inclined lower face of the slide, and provided with an upper face engageable with said blocking-face of the slide, and provided with a rear face engageable with said stop-face of the slide, link means connected to said slide 95 and connected to said breechblock, and a firing member movable to firing position by engagement with said rear contacting means of the slide when said slide is moved rearwardly.

13. In a firearm, in combination, a frame 100 of said firearm provided with an abutment face, a slide movable rearwardly and forwardly on said frame and provided with an inclined lower face, and provided with a blocking-face, and provided with a stop-face, and provided with rear contacting means, a breechblock movable rearwardly by powder gases prior to rearward movement of said slide and comprising a firing-pin, and provided with a lower-face engageable with said abutment face of the frame, and provided with a front-face engageable with said inclined lower face of the slide, and provided with an upper face engageable 105 with said blocking-face of the slide, and provided with a rear face engageable with said stop-face of the slide, link means connected to said slide and connected to said breechblock, and a firing member movable to firing position by engagement with said rear contacting means of the slide when said slide is moved rearwardly.

tacting means of the slide when said slide is moved rearwardly, and movable to fired position and engageable with said firing-pin.

14. In a firearm, in combination, a frame 5 of said firearm provided with an abutment face, a slide movable rearwardly on said frame provided with an inclined lower face, and provided with a blocking-face, and provided with a stop-face, and provided with a 10 guide-face, a breechblock movable rearwardly by powder gases prior to rearward movement of said slide provided with a lower-face engageable with said abutment face of the frame, and provided with a 15 front-face engageable with said inclined lower face of the slide, and provided with an upper-face engageable with said blocking-face of the slide, and provided with a rear face engageable with said stop-face of 20 the slide, and provided with an end engaging said guide-face of the slide, and links pivotally connected to said slide and pivotally connected to said breechblock.

15. In a firearm, in combination, a frame 25 of said firearm provided with an abutment face, a slide movable rearwardly on said frame provided with an inclined lower face, and provided with a blocking-face, and provided with a stop-face, and provided with a 30 guide-face, and provided with a roller, a breechblock movable rearwardly by powder gases prior to rearward movement of said slide and comprising a firing-pin, and provided with a lower face engageable with 35 said abutment face of the frame, and provided with a front face engageable with said inclined lower face of the slide, and provided with an upper face engageable with said blocking-face of the slide, and provided with a 40 rear face engageable with said stop-face of the slide, and provided with an end engaging said guide-face of the slide, links pivotally connected to said slide and pivotally connected to said breechblock, and 45 a firing member movable to firing position by engagement with said roller of the slide when said slide is moved rearwardly.

16. In a firearm, in combination, a frame 50 of said firearm provided with an abutment face, a slide movable rearwardly and forwardly on said frame provided with an inclined lower face, and provided with a blocking-face, and provided with a stop-face, and provided with a guide face, and 55 provided with a roller, a breechblock movable rearwardly by powder gases prior to rearward movement of said slide and comprising a firing-pin, and provided with a lower face engageable with said abutment 60 face of the frame, and provided with a front face engageable with said inclined lower face of the slide, and provided with an upper face engageable with said blocking-face of the slide, and provided with an 65 end engaging said guide-face of the slide,

links pivotally connected to said slide and pivotally connected to said breechblock, and a firing-member movable to firing position by engagement with said roller of the slide when said slide is moved rearwardly, and 70 movable to fired position and engageable with said firing-pin.

17. In a firearm, in combination, a frame 75 of said firearm provided with retarding means, a slide movable rearwardly on said frame and provided with faces for engagement, a breechblock initially movable rearwardly relative to rearward movement of said slide and engageable with said retarding means of the frame when so initially 80 moved, and engageable with said faces of the slide subsequent to engagement with said retarding means, and means connected to said slide and connected to said breechblock providing thrust, tension and guiding 85 means.

18. In a firearm, in combination, a frame 90 of said firearm provided with retarding means, a slide movable rearwardly on said frame and provided with faces for engagement, a breechblock initially movable rearwardly relative to rearward movement of said slide and engageable with said retarding means of the frame when so initially 95 moved, and engageable with said faces of the slide subsequent to engagement with said retarding means, means connected to said slide and connected to said breechblock providing thrust, tension and guiding means, and a firing member movable to firing 100 position by rearward movement of said slide.

19. In a firearm, in combination, a frame 105 of said firearm provided with retarding means, a slide movable rearwardly and forwardly on said frame and provided with faces for engagement, a breechblock comprising a firing-pin and initially movable rearwardly relative to rearward movement of said slide, and engageable with said retarding means when so initially moved, and engageable with said faces of the slide subsequent 110 to engagement with said retarding means, means connected to said slide and connected to said breechblock providing thrust, tension, 115 and guiding means, and a firing member movable to firing position by rearward movement of said slide, and movable to fired position and engageable with said firing-pin.

20. In a firearm, in combination, a frame 120 of said firearm provided with retarding means, a slide movable rearwardly on said frame provided with faces for engagement and provided with guiding means, a breechblock initially movable rearwardly relative 125 to rearward movement of said slide and engaging said guiding means of the slide, and engageable with said retarding means of the frame when so initially moved, and engageable with said faces of the slide subsequent 130

- to engagement with said retarding means, and means pivotally connected to said slide and pivotally connected to said breechblock providing thrust, tension and guiding means.
21. In a firearm, in combination, a frame of said firearm comprising retarding means, a slide movable rearwardly on said frame provided with faces for engagement and 10 provided with guiding means, and provided with rear contacting means, a breechblock initially movable rearwardly relative to rearward movement of said slide, and engaging said guiding means of the slide, and 15 engageable with said retarding means of the frame when so initially moved, and engageable with said retarding means, means pivotally connected to said slide and pivotally connected to said breechblock providing thrust, tension and guiding means, and a 20 firing member movable to firing position by rearward movement of said slide by engagement with said rear contacting means of the slide.
22. In a firearm, in combination, a frame 25 of said firearm, a slide movable rearwardly and forwardly on said frame provided with faces for engagement and provided with guiding means, a breechblock initially movable rearwardly relative to rearward 30 movement of said slide, and engaging said guiding means of the slide, and engageable with said retarding means of the frame when so initially moved, and engageable with said faces of the slide subsequent to 35 engagement with said retarding means, means pivotally connected to said slide and pivotally connected to said breechblock providing thrust, tension, and guiding means, and a firing member movable to firing position by rearward movement of said slide by engagement with said rear contacting 40 means of the slide, and movable to fired position and engageable with said firing pin.
